[57] CLAIM

The ornamental design for an ornamental chain, as shown and described.

DESCRIPTION

FIG. 1 is a front view of an ornamental chain showing my new design;

FIG. 2 is a right side view of the chain shown in FIG. 1;

FIG. 3 is a rear view of the chain of FIGS. 1 and 2;

FIG. 4 is a left side view of the chain of FIGS. 1, 2 and 3;

FIG. 5 is a top view of the chain; and,

FIG. 6 is a bottom view of the chain.

The dot dash lines, shown on the ends of each figure, are representative of the indeterminate length of the chain.
